UNITED STATES PATENT OFFICE.

REINHOLD GLINKA, OF NEW YORK, N. Y.

DESIGN FOR A FRAME FOR TOY ENGINES.

SPECIFICATION forming part of Design No. 32,236, dated February 13, 1900.

Application filed January 16, 1900. Serial No. 1,696. Term of patent 31 years.

To all whom it may concern:

Be it known that I, REINHOLD GLINKA, a citizen of the United States, residing at New York, in the borough of Brooklyn and State 5 of New York, have invented and produced a new and original Design for Frames for Toy Engines, of which the following is a specification, reference being had to the accompanying drawings, forming a part thereof, and in 10 which—

Figure 1 is a side elevation, and Fig. 2 is a plan view.

As shown in the drawings, the leading or material feature of my design consists of an 15 oblong base with sloping sides, from one end of which rises a vertical cylinder having a lower portion, an intermediate smaller portion, and an upper portion formed at its base with an ogee curve, a straight neck above the 20 ogee curve, a bulge above the neck, and a flaring extremity.

In the drawings, A indicates the oblong base, having at one end a circular extension A', both being formed with sloping sides a.

Extending vertically upward from the circular extension A' is a cylindrical device B, having a lower cylindrical portion b, an intermedial smaller portion b', and an upper portion b² b³ b⁴ b⁵, b² indicating an ogee curve, b³ a straight neck, b⁴ a bulge or bead, and b⁵ 30 a flaring extremity. Short ribs or ears are arranged at opposite sides of the intermediate portion b'.

A tapered cylindrical standard D and two standards E, each having a rounded head e, 35 rise from the base A.

What I claim is—

The design for a frame for toy engines, as described and shown.

In testimony that I claim the foregoing as 40 my invention I have signed my name in presence of two subscribing witnesses.

REINHOLD GLINKA.
